Des. 185,381
Patented June 2, 1959

185,381

DISPLAY STAND FOR MECHANIC'S HAND TOOLS

Robert H. Mowrey, Jr., Portland, and Charles L. West, Milwaukie, Oreg., assignors to Pendleton Tool Industries, Inc., Los Angeles, Calif., a corporation of California

Application February 14, 1958, Serial No. 49,653

Term of patent 14 years

(Cl. D80—9)

Figure 1 is a perspective view of a display stand for mechanic's hand tools showing our new design;

Figure 2 is a top plan view thereof; and

Figure 3 is an end elevational view thereof.

We claim:

The ornamental design for a display stand for mechanic's hand tools, substantially as shown.
